CLAIM

The ornamental design for a box pleat curtain, as shown and described.

DESCRIPTION

FIG. 1 is a front perspective view of a box pleat curtain, showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view.

The box pleat curtain is shown with a symbolic break in its length and width. The appearance of any portion between the break lines forms no part of the claimed design.
